UNITED STATES PATENT OFFICE.

EDMOND PICAULT, OF STOKE-UPON-TRENT, ENGLAND, ASSIGNOR TO MADDOCK & MILLER, OF NEW YORK, N. Y., A CORPORATION OF NEW YORK.

DESIGN FOR A PLATE OR SIMILAR ARTICLE.

47,009.

Specification for Design.

Patented Feb. 23, 1915.

Application filed October 19, 1914. Serial No. 867,545. Term of patent 3½ years.

To all whom it may concern:

Be it known that I, EDMOND PICAULT, a citizen of the French Republic, residing at 576 Leek road, Stoke - upon - Trent, in the county of Stafford, England, have invented a certain new, original, and ornamental Design for a Plate or Similar Article, of which the following is a specification.

In the accompanying drawing, the figure is a plan view of a plate, showing the design.

I claim:

The ornamental design for a plate or similar article as shown.

In testimony whereof I affix my signature in presence of two witnesses.

EDMOND PICAULT.

Witnesses:

W. H. TAYLOR,
J. H. COPELSTALTE.
